[57] CLAIM

The ornamental design for a cassette player with tuner, as shown.

DESCRIPTION

FIG. 1 is a front, top and right side perspective view of a cassette player with tuner showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof;

FIG. 8 is a front, top and right side perspective view of a second embodiment of the cassette player with tuner illustrated in FIG. 1;

FIG. 9 is a front elevational view of the embodiment disclosed in FIG. 8;

FIG. 10 is a right side elevational view of the embodiment disclosed in FIG. 8;

FIG. 11 is a top plan view of the embodiment disclosed in FIG. 8;

FIG. 12 is a rear elevational view of the embodiment disclosed in FIG. 8;

FIG. 13 is a left side elevational view of the embodiment disclosed in FIG. 8; and,

FIG. 14 is a bottom plan view of the embodiment disclosed in FIG. 8.
